UNITED STATES PATENT OFFICE.

LUCKEY C. DAVIS, OF MOUND BAYOU, MISSISSIPPI.

SAFETY WHIP-HOLDER.

982,258.

Specification of Letters Patent. Patented Jan. 24, 1911.

Application filed November 9, 1909. Serial No. 527,042.

To all whom it may concern:

Be it known that I, LUCKEY C. DAVIS, a citizen of the United States, residing at Mound Bayou, in the county of Bolivar 5 and State of Mississippi, have invented certain new and useful Improvements in Safety Whip-Holders, of which the following is a specification.

The primary object of my invention is a 10 simple, durable and efficient construction of safety whip holders for use on buggies, wagons, or similar vehicles, and the invention consists in certain constructions, arrangements, and combination of the parts 15 that I shall hereinafter fully describe and claim.

For a full understanding of the invention reference is to be had to the following description and accompanying drawing, in 20 which:

Figure 1 is a perspective view illustrating the application of my improved whip holder. Fig. 2 is a longitudinal sectional view of the same on an enlarged scale. Fig. 25 3 is a detail sectional view taken through the middle of the device at right angles to the section of Fig. 2. Fig. 4 is a horizontal section on the line 4—4 of Fig. 2, and Fig. 5 is a detail view illustrating one of the 30 clips that may be employed.

Corresponding and like parts are referred to in the following description and indicated in all the views of the accompanying drawing by the same reference characters.

35 My improved whip holder comprises a socket 1 which may be composed of any desired substance or material, and of any desired size or design, the same being preferably covered around its sides and bottom by 40 a sheathing 2 of leather or some other material which will add to the attractiveness of the device.

The socket 1 may be secured to the dashboard of a vehicle in any desired way, as 45 by a pair of lower clips 3 designed to be attached to the rib of the dashboard, and an upper spring clip 4. If desired the socket may be provided with extra openings 5 to receive bolts by which the device may be 50 secured to a wagon dashboard.

The socket 1 is recessed or bifurcated from a point at any predetermined distance above its lower end and up to its upper end, whereby to form a chamber 6 for the whip holding 55 member 7. In the present instance, this whip holding member consists of a strip of

spring metal or material returned upon itself to form two substantially parallel arms integrally connected with each other at their lower ends, one of said arms being rigidly 60 connected throughout its length to that wall of the chamber 6 against which it lies, while the other arm is free to be sprung inwardly whereby to clamp the whip stock after the same has been inserted in between the arms. 65

8 designates a guiding plate which is secured to the upper end of the socket and which is formed with an opening through which the whip stock is designed to be inserted, this opening guiding the whip stock 70 properly in between the edges of the clamping member. These edges are preferably covered with rubber, or the like, so as to prevent injury to the whip stock or handle.

In order to clamp the whip handle and 75 securely lock it in place after it has been inserted in between the arms of the clamping member 7, I provide a cam lever 8' which is journaled by means of trunnions formed in the socket, as shown, and which 80 works in a slot 9 formed in one of the bifurcated ends of the socket, the handle of the lever being located on the outside of the socket, as clearly illustrated in the drawing. By turning the handle of this cam lever 8' 85 down against the edge of the socket 1, the cam lever will be pressed against the movable or spring arm of the clamping member and will move it toward the other arm so that both arms will securely hold the whip 90 stock after it has been inserted in place.

10 designates a locking plate which is provided with a lock in the nature of a trunk lock designed to engage the handle of the lever 8'. Said handle is provided with a 95 keyhole, as shown. Preferably secured to the handle of the lever 8' is a closure for the keyhole, the same consisting of a plate 11 pivoted at one end to the handle and formed with a bulged or dished portion 12 adapted 100 to snap into the keyhole when the plate is moved to a position where it will cover the same.

13 designates a spring which is secured to the handle of the lever 8', the free end of the 105 spring bearing upon the plate and serving to hold it in place as against accidental displacement.

From the foregoing description in connection with the accompanying drawing, the 110 operation and advantages of my improved whip holder will be apparent. In the prac-

tical use of the device, the whip holder is inserted down between the two arms of the clamping member 7 and after it has been thrust down as far as possible, the cam lever 8 is manipulated to clamp the two arms upon the whip handle or stock. The handle of the cam lever is then locked in the plate 10 and the owner of the vehicle may leave the same feeling assured that his whip will be safely held until he returns.

Having thus described the invention what is claimed as new is:—

The herein described whip holder, comprising a socket bifurcated from its upper end to a point short of its lower end, a sheathing covering the socket and closing

the sides of the forked portion thereof, whereby to form a chamber, spring arms mounted in the chamber, one of said arms being rigidly fastened therein while the other arm is free, the socket being formed at its upper end with an opening leading into the chamber through the sheathing, and a cam lever journaled in said opening and adapted to engage the free clamping arm. 20 25

In testimony whereof I affix my signature in presence of two witnesses.

LUCKEY C. DAVIS. [L.S.]
